UNITED STATES PATENT OFFICE.

JOHN F. GUBBINS, OF CHICAGO, ILLINOIS.

WRINGER GUARD.

Application filed May 21, 1921. Serial No. 471,332.

To all whom it may concern:

Be it known that I JOHN F. GUBBINS, a citizen of the United States, residing at Chicago, in the county of Cook and State of Illinois, have invented certain new and useful Improvements in Wringer Guards, of which the following is a specification.

This invention relates to a guard and hopper adapted for use with a clothes wringer and has for its purpose to provide improvements in safety attachments for wringers for preventing injury to the hands of the operators. The present invention is a modification of the inventions covered in the United States Patents Nos. 1,161,244 and 1,161,245, granted to me under date of November 23, 1915, as the assignee of William Pawlak.

The principal object of the invention is to provide an improved hopper or wringer guard having means for positively feeding the clothes between the rollers of the wringer. Another object is to provide a hopper having a movable wall provided with perforations to permit the escape of soap-suds and the like from the hopper. A further object is to provide a hopper having a movable wall pivoted at its upper edge and provided with means along the lower edge thereof to prevent the fingers of the operator from slipping between the rollers when the wall is moved inwardly to feed the clothes to the wringer. Another object is to provide a hopper having a roller along the upper edge of the movable wall to eliminate the friction and facilitate the passage of the clothes into the rollers of the wringer.

The nature of the invention will be understood from the following specification taken with the accompanying drawings in which one embodiment is illustrated.

In the drawing—

Figure 1 shows an end elevation of a wringer with the present invention applied thereto, a portion of the structure being broken away to show the rollers of the wringer and the hopper in vertical section;

Fig. 2 shows a side elevation of the hopper and wringer; and

Fig. 3 shows a side elevation of a bracket for supporting the hopper or wringer guard on the wringer.

The top cross member of the wringer 10 is secured at its ends in any suitable manner, as shown at 11, to the upper ends 55 of the side frame members 12. The lower

ends of the side members are recessed at 13 to engage the side of a washtub or washing machine and the wringer is held in position on the tub by the clamping screws 14. The usual oppositely rotating rollers 15 and 16, between which the clothes pass and by which the water is squeezed out of the clothes, are journalled at their ends in bearings located within vertical slots formed in the side members of the frame. A leaf spring 17 is located above the upper roller 15 and bears at its ends on the bearings of said roller, thereby forcing it into yielding contact with the lower roller 16, the pressure with which the upper roller contacts with the lower roller is regulated by means of the adjusting screw 18 which threadedly engages the top member at the center thereof and bears at its lower end upon the upper surface of the spring 17. Beneath the rollers 15 and 16, there is located a board 19 which is pivoted in the side frame members, as shown at 20, and is therefore capable of being inclined in either direction with respect to the vertical plane of the wringer. Below the board 19 and between the side frame members is a rod 21 which rigidly engages the side frame members at 22 and holds the lower ends of these members in fixed relation to each other. The lower side of the board 19 carries a leaf spring 23 which frictionally engages the rod 21 and thereby operates to hold said board at any desired inclination in order to drain the water extracted from the clothes into any suitable vessel at either side of the wringer.

One end of the shaft of the roller 16 extends through the side frame and is operatively connected to a source of power. The shafts of the rollers 15 and 16 also carry intermeshing gear wheels located within the side frames whereby rotation is communicated from one roller to the other (not shown in the drawings).

The foregoing features are shown and described for the purpose of illustrating the adaptation thereto of the wringer guard 25 of the present invention which comprises end walls 26 united by an integrally formed lower wall 27 and a movable wall 28 which is provided at its ends with inwardly directed flanges 29 having trunnions 30 projecting longitudinally therefrom at their upper ends and pivotally engaging the end walls 26. The movable wall 28 is provided

with a plurality of perforations 31 which permit the soap-suds to flow out of the hopper and the lower edge of the movable wall is provided with a longitudinal flange 32 extending outwardly therefrom and adapted to prevent the slipping of the fingers of the operator inwardly toward the rollers 15 and 16 when the wall 28 is moved inwardly about its pivots. The upper edge 10 of the wall 28 is provided with a longitudinal notch or recess 33 having a roller 34 located therein and provided at its ends with trunnions 35 which pivotally engage bearings 36 carried by the end flanges 29.

15 The inner edges of the end walls 26 are adapted to rest upon the plates 38 of the end frames and the inner extremity of the lower wall 27 is adapted to project between these end frames toward the rollers, slightly below the line of contact of the rollers, as shown in Fig. 1.

20

The guard is held in this position by means of lugs or trunnions 39 which project longitudinally from the upper inner 25 corners of the end walls and rest on the hooks 40 which are formed on brackets 41 adapted to rest upon the upper cross member 10. These brackets have the form illustrated particularly in Fig. 3 and are held in 30 position by clamping screws 42. Hooks are provided on both sides of the bracket so that the wringer guard can be located on either side of the wringer. After placing the brackets on the upper cross member of 35 the wringer, the hopper is suspended from the hooks 40 at one side of the wringer and occupies the position shown in Figs. 1 and 2.

When the wringer is in operation, the 40 clothes are passed over the roller 34 into the hopper. In order to force the clothes between the rollers 15 and 16, the operator places her hand against the lower portion 45 of the movable wall 28 and pushes it inwardly, thereby positively forcing the clothes between the rollers. As the rollers rotate they draw the clothes over the roller 34 at the upper edge of the movable wall and the hand of the operator is prevented 50 from slipping over the lower edge of the movable wall by the outwardly directed flange 32. The perforations permit the soap-suds to escape from the hopper in-

stead of passing through the wringer as they would be liable to do if no means of escape were provided.

Although I have shown and described one form of the invention for purposes of illustration, it will be understood that it can be constructed in various other forms without departing from the scope of the appended claims.

I claim:

1. A device for feeding clothes to a wringer, comprising a hopper having a movable wall pivoted at the upper part thereof to swing inwardly towards the wringer, and a flange projecting outwardly from the lower part of said wall for preventing the fingers of the operator from passing over the lower edge of said wall into the wringer.

2. A wringer guard comprising a lower wall, end walls extending upwardly from said lower wall and an outer wall mounted between said end walls and extending outwardly and upwardly from the outer part of said lower wall, said outer wall being pivoted adjacent its upper edge to swing inwardly between said end walls to force the clothes from said wringer guard into the wringer.

3. A wringer guard comprising a lower wall, end walls, and a movable wall extending upwardly from said lower wall and movable inwardly between said end walls, said movable wall being pivoted adjacent its upper edge, and a roller extending along the upper edge of said movable wall.

4. A wringer guard comprising a lower wall, end walls, and a movable wall extending upwardly from said lower wall and movable inwardly between said end walls, said movable wall being pivoted adjacent its upper edge and being provided with perforations.

5. A wringer guard comprising a lower wall, end walls, and a movable wall extending upwardly from said lower wall and movable inwardly between said end walls, said movable wall being pivoted adjacent its upper edge and being provided with perforations, and a longitudinal flange extending outwardly from the lower edge of said movable wall.

In testimony whereof, I have subscribed my name.

JOHN F. GUBBINS.
